UNITED STATES PATENT OFFICE.

SIGMUND KOHN, OF NEW YORK, N. Y., ASSIGNOR OF ONE-HALF TO
HARRY BROOKS, OF NEW YORK, N. Y.

SOLDERING-TOOL.

No. 835,794.

Specification of Letters Patent.

Patented Nov. 13, 1906.

Application filed September 21, 1905. Serial No. 279,429.

To all whom it may concern:

Be it known that I, SIGMUND KOHN, a citizen of the United States, and a resident of New York, in the county of New York and 5 State of New York, have invented certain new and useful Improvements in Soldering-Tools, of which the following is a specification.

The present invention pertains to soldering-tools which are heated by means of a gas-flame, and has for its object to insure a uniform strong heating of the copper bit and to allow of its being used for both soft and hard soldering.

15 In order to make my invention more clear, the same is illustrated in the accompanying drawings, in which—

Figure 1 is a longitudinal section of the tool, the copper bit or bolt being removed. 20 Fig. 2 is a longitudinal section of the forward end of the tool carrying the copper bit or bolt. Fig. 3 is a cross-section through line $x x$ of Fig. 2, showing the adjustment of the bit. Fig. 4 is a cross-section through line $y y$ of Fig. 1. Fig. 5 is a cross-section through line $z z$ of Fig. 1. Fig. 6 is a cross-section through line $w w$ of Fig. 1. Fig. 7 is a cross-section through line $v v$ of Fig. 1.

With reference to the drawings, a denotes 30 a hollow wooden handle containing the supply-pipe b , which is to be connected with the gas-pipe leading from a suitable source. The forward end of the pipe b is screw-threaded to receive a nut c . Upon the screw-threaded 35 end of the nut c a pipe d is fixed, which carries at its forward end a mouthpiece e , adapted to hold the wedge-shaped copper bit or bolt f . In the forward open end of the nut c a small mouthpiece g , having a narrow passage i , is 40 suitably fixed. This mouthpiece projects into the pipe d and is provided with a narrow bore j , which intersects the bore i of the mouthpiece and in which works a pin-valve k , arranged in a casing l . The casing l is 45 fixed at the rear end of the pipe d above the mouthpiece g . The spindle k' and the pin-valve k are smaller in diameter than that of the inner circumference of the casing l , so that an air-channel m is formed around the 50 pin-valve. Apertures are arranged in the circumference of the casing to allow the admission of air into the pipe d . Openings d' are also provided at the inner end of the pipe

d , and a cap of wire-gauze n' or the like is fitted around said openings d' to form a Bunsen burner. A shell l' of any suitable shape is arranged over the wire-gauze cap n' and a part of the pipe b and is fixed to the forward end of the wooden handle a . This shell l' has openings o , adapted to register with the 60 openings in the pipe d , thus allowing air to pass through the gauze-cap n' and the apertures d' into the pipe d . At the rear end the shell l' is also provided with a series of small apertures o' , which apertures allow admission 65 of air from the rear. At the front extremity of the pipe d a rotary valve p is arranged in a casing q , fixed in the pipe d and projecting outward therefrom. The valve p consists of a narrow tube having an opening p' , and 70 the casing q has a corresponding opening q' , with which the opening p' is adapted to register when in order to open the valve the latter is turned around its vertical axis.

The mouthpiece e , which is removably attached to the forward end of the pipe d , is provided at its rear with perforations $t t$, through which the ignition of the gas mixture entering the mouthpiece through the pipe d is effected, the rear part of the mouthpiece thus forming the ignition-chamber. The front part of the mouthpiece is preferably of rectangular shape and provided with openings $r r'$ to engage the head of the copper bit f , the latter being adapted to engage 85 with one of the openings r of the mouthpiece when it is to be used as a hammer.

To secure the copper bit in position when in engagement with the mouthpiece, set-screws $s s$ are arranged to work in the side 90 walls of the mouthpiece.

The pin-valve k controls the admission of gas from the pipe b into the pipe d . When the valve p , which controls the blast, is closed and the valve k is raised or opened, the gas 95 flows through the pipe b and mouthpiece g into the pipe d , and being ignited in the mouthpiece e burns as an ordinary blue flame. On opening the blast-valve p the air admitted through the latter will transform the ordinary flame into a blast-flame, which will have a great heating capacity, so that the bit f will be rapidly and strongly heated. In moving the soldering-iron to and fro during its operation air will be supplied through the 105 apertures o', o , and n .

A further important feature of my invention is that the construction of the tool permits the latter to be used as a blowpipe for hard soldering. To this end it is necessary 5 to remove the mouthpiece *e* and the copper bit *f*.

What I claim, and desire to secure by Letters Patent, is—

In combination with a soldering-tool, of a 10 mouthpiece detachably fixed to the soldering-tool, said mouthpiece having a square cross-section in front and a gradually-reduced rear portion, the square front portion being provided with an opening at its forward extremity, and with openings in two 15 opposite walls, set-screws arranged in the

two other side walls of the mouthpiece oppositely to each other, and a copper bit, to be carried by said mouthpiece, and being capable of being engaged therewith either longitudinally through the front opening, or transversally through the opposite side openings and of being secured in either position by the said set-screws so as to serve both for soft and hard soldering, substantially as set forth. 20 25

Signed at New York, in the county of New York and State of New York, this 20th day of September, A. D. 1905.

SIGMUND KOHN.
